UNITED STATES PATENT OFFICE.

HORACE MIDDAUGH, OF SEATTLE, WASHINGTON.

REFUSE-BURNER.

1,199,403.

Specification of Letters Patent. Patented Sept. 26, 1916.

Application filed March 29, 1916. Serial No. 87,616.

To all whom it may concern:

Be it known that I, HORACE MIDDAUGH, a citizen of the United States, and resident of the city of Seattle, county of King, State of Washington, have invented certain new and useful Improvements in Refuse-Burners, of which the following is a specification.

My invention relates to refuse burners, and has been particularly designed for use in disposing of the refuse from saw mills.

The object of my invention is to provide a simple and cheap form of construction, which shall have a large capacity, and involving in its construction such principles as contribute to the efficiency of the device in action, and its longevity.

The scope of my invention may be determined by an inspection of the claims terminating this specification. In the accompanying drawings I have shown the form of construction, which is now preferred by me.

Figure 1 is an elevation and partial section of a device constructed in accordance with my invention. Fig. 2 is a partial plan view, a portion of this having the outer skin broken away, to better show the grates within.

The general shape of the device chosen is that of a cone. This form gives a large base, whereby the pile of refuse may be of considerable size, without the same being brought into actual contact with the outer skin. By reason of this, excessive heating of this outer skin, and in consequence wastage thereof, and deterioration, is in a measure prevented. The material of construction is preferably iron. This would involve struts or inclined vertical posts 1, to the inner side of which is secured plates to form the inner skin 2, and to the outer sides of which are secured plates to form the outer skin 3.

The inner skin 2 is imperforate, except as it is necessary to provide an opening, as 20, through which the refuse is fed. The outer skin 3 is provided with an opening 30, said opening consisting in effect of a space extending entirely about the bottom of the burner, through which the air will have free access to the space between the two skins.

At the upper end of the cone the space between the two skins is left freely open, whereby air will enter through the opening 3 at the base, pass upwardly between the two skins, and be discharged at the upper end of the wall. This produces a circulation of

cooling air, which prevents excessive heating of the plates, and thereby contributes to their longevity.

At the upper end of the cone is a screening hood 4, this hood being of any suitable construction. This hood is preferably made at its base of a size to fit upon the outer skin 3, whereby the discharge of cooling air from the space between the two skins is made directly into the base of the hood.

The air for combustion is supplied through a grate, or grates 5, which occupy a considerable space, covering the central portion of the base of the cone. Air is provided for this purpose through a tunnel, or tunnels 6, which extend to and beyond the base of the cone. It is my intention to provide all of the air for combustion purposes through these grates.

This form of construction is one which is cheap in first cost, has a considerable capacity, because of the fact that it will accommodate a large sized pile, and by reason of the air circulating between the two skins, 80 the overheating of the plates forming the walls is prevented. At the same time, furnishing of air for combustion through the base of the pile, causes a more rapid and effective combustion than when the air is simply provided to the outside surface of the pile.

What I claim as my invention is:

1. A refuse burner comprising a base having a grate comprising the central area thereof, and channels for supplying air to said grate, upwardly-extending struts having their lower ends carried by the base well outward of the grate area and inclined to outline a frustum of a cone, a casing secured upon the outer side of said struts, a second casing secured to the inner side of said struts and forming with the first casing a hollow wall, said hollow wall having an opening extending entirely about the base thereof to admit outside air to the hollow wall but not to the combustion chamber, said wall having a refuse feeding opening near its top.

2. A refuse burner comprising a base having a grate comprising the central area thereof, and channels for supplying air to said grate, upwardly-extending struts having their lower ends carried by the base well outward of the grate area and inclined to outline a frustum of a cone, a casing secured upon the outer side of said struts and ex-

tending from the top to a point above the base, a second casing secured to the inner side of said struts and extending from the top to the base and forming, with said first casing, a hollow wall open at the top and open to the outer air at the bottom.

3. A refuse burner comprising a base, upwardly-extending struts, a casing secured upon the outer side of said struts and extending from the top to a point above the base, a second casing secured to the inner side of said struts, and extending from the top to the base, and forming with said first casing a hollow wall open at the top, and open to the outer air at the bottom, and a screening hood secured to the tops of said struts and surrounding the upper outlet of said hollow wall, whereby the air therefrom is discharged within the hood.

4. A refuse burner comprising a base 20 having draft channels therein, upwardly extending struts mounted thereon, an outer casing secured upon the outer side of said struts and extending from the top thereof to near the base, an inner casing secured 25 upon the inner side of said struts and extending continuously from their top to the base, said casings forming a hollow wall having an inlet opening for outside air at the bottom, and an outlet opening at the top, 30 and a screening hood secured at the top of said struts, and including the top of the burner and the outlet opening of the hollow wall.

Signed at Seattle, Washington, this 21st 35 day of March, 1916.

HORACE MIDDAUGH.
